(Continued)Primary Examiner — Keli L Hill(74) Attorney, Agent, or Firm — Egan, Peterman, Enders & Huston LLP(57) CLAIM

The speaker sound bar with side mounts, as shown and described.

DESCRIPTION

FIG. 1 is a front and right side perspective view of a speaker sound bar with side mounts, embodying our new design;
 FIG. 2 is a front elevation view thereof;
 FIG. 3 is a rear elevation view thereof;
 FIG. 4 is a cross-sectional view thereof taken between axes A-A and B-B of FIG. 3;
 FIG. 5 is a left side elevation view thereof;
 FIG. 6 is a right side elevation view thereof;
 FIG. 7 is a top plan view thereof; and,
 FIG. 8 is a bottom plan view thereof.

The broken lines shown are included for the purpose of illustrating portions of the speaker sound bar with side mounts that form no part of the claimed design.

1 Claim, 3 Drawing Sheets(56)
